BY H. G. Underwood

ATTORNEY.

UNITED STATES PATENT OFFICE.

GEORGE MILAN CONWAY, OF MILWAUKEE, WISCONSIN.

DESIGN FOR A GRATE-BAR.

SPECIFICATION forming part of Design No. 25,533, dated May 19, 1896.

Application filed February 17, 1896. Serial No. 579,654. Term of patent 14 years.

To all whom it may concern:

Be it known that I, GEORGE MILAN CONWAY, a citizen of the United States, residing at Milwaukee, in the county of Milwaukee and State of Wisconsin, have invented and produced a new and original Design for a Grate-Bar; and I do hereby declare the following to be a full, clear, and exact description of the same, reference being had to the accompanying drawings, forming a part thereof, in which—

Figure 1 represents a perspective view of a grate-bar embodying my new design. Fig. 2 is a transverse sectional view on the line 2 2 15 of Fig. 1, and Fig. 3 is an end elevation.

My design relates to the new and original shape or configuration of the article.

The leading features of this design for a grate-bar comprise a body of much greater length than its width and of much greater width than its height, the upper surface of said body being drawn transversely on the arc of a circle, with two vertically-disposed parallel longitudinal members projecting downward to an equal distance below said upper surface, between which members the said upper surface is interrupted at approximately equal distances by straight-walled spaces of the form of oblong parallelograms, the width and length of said spaces being approximately equal to the width and length of the solid portions of the upper surface of said body between the spaces and between the described longitudinal members and with projecting portions beyond the outside lines of said longitudinal members, extending downward an equal distance therewith, said projecting portions being approximately in line with the described interior solid portions, with equal spaces between them, the upper surfaces of said projecting portions continuing on the line of the described arc of a circle for a short distance, and then abruptly tending downward and outward in short rounded nearly-oblique lines, and thence tending inward in longer nearly-oblique but somewhat-rounded lines

to the plane of the bottom of the described longitudinal members, the length of the lower and longer inwardly-tending side lines of said projecting portions being more than double 50 the length of the upper and shorter outwardly-tending side lines of said projecting portions.

Minor features of this design include one end (shown in Fig. 3) with the lower surface thereof drawn on the arc of a smaller circle 55 than that on which the upper surface is drawn and with a central opening comprising a complete and still smaller circle; also the other end (shown in Fig. 1) with two vertically-disposed members projecting from lines just inside the inner lines of the heretofore-described longitudinal members and extending downward to a greater distance than the downward projection of said longitudinal members, the inner walls of said two vertically-disposed 60 end members being drawn on straight lines to a point or plane above the lower plane of said longitudinal members, and thence united on the arc of a circle conforming in diameter to the complete circle of the other end; also 65 a central downward-projecting member (best shown in Fig. 2) whose exterior or side edges are drawn on the lines of two complementary or oppositely-disposed ogees, beginning at the points of intersection of the said longitudinal members and the described projecting portions and continuing downward in rounded lines to a point below the plane of the lowest projecting end members, the two 70 side edges of this last-named downwardly-projecting member being united or merged together on the arc of a circle.

What I claim is—

The design for a grate-bar substantially as shown and described. 85

In testimony whereof I affix my signature in presence of two witnesses.

GEORGE MILAN CONWAY.
